UNITED STATES PATENT OFFICE.

JASON B. MOODY, OF DALLAS, TEXAS.

LOOSE-LEAF BINDER.

1,244,756.

Specification of Letters Patent. Patented Oct. 30, 1917.

Application filed November 6, 1916. Serial No. 129,656.

To all whom it may concern:

Be it known that I, JASON B. MOODY, citizen of the United States, residing at Dallas, in the county of Dallas and State of Texas, 5 have invented certain new and useful Improvements in Loose-Leaf Binders, of which the following is a specification.

In the construction of a loose-leaf binder it would be of great advantage to have the 10 leaves "fanned" when the binder is opened, so that the leaves could be more readily separated at the desired place and this point easily located by passing the index finger along the beveled edge formation into which 15 the leaves are moved when "fanned".

One of the features of my invention is embodied in a loose-leaf binder that will spread or "fan" the leaves when its backs or binder members are separated.

20 Another feature of the invention is included in posts or leaf supports extending between the binder members and coöperating with the loose leaves in such a manner that each leaf to a certain degree positions 25 itself when dropped into the binder.

Another point involves the relative displacing longitudinally of one binder member from the other binder member and at the same time separating the members laterally.

In carrying out the invention a pair of elongated binder members are provided with laterally extending posts or leaf supports pivoted thereto, the outer ends of the 35 posts of one member extending into or telescoping the ends of the posts of the other member, so that when the members are separated laterally the posts will still remain in engagement.

40 Means connected with one member and attached to the other is provided for swinging one of the members away from the other and longitudinally displacing it at the same time whereby the posts are swung at an 45 angle and the leaves spread or "fanned".

The leaves have notches coöoperating with the posts which have ridges, whereby the posts are received in the notches and the leaves slide to position.

50 The invention will be more readily understood from a perusal of the following specification and by reference to the accompanying drawings, in which an example of the invention is shown and wherein:

55 Figure 1 is a rear view of the binder in

its closed position, one of the members having portions in section,

Fig. 2 is a similar view with the binder open or extended and the leaves spread.

Fig. 3 is a perspective sectional detail 60 with the major portion of the leaves removed, and

Fig. 4 is a detail of one of the posts and a portion of one of the leaves.

In the drawings the numerals 1 and 2 65 designate opposed binder members having the nature of elongated strips and formed of suitable material. Tongue pieces 3 are inserted in one edge of the members and are attached to hinge pintles 4 by clips 5; while 70 companion clips 6 embrace the pintles from the opposite side and are secured to back boards 7, which are thus hinged to the binder members. It is pointed out that the manner of hinging the back boards to the 75 binder members is optional and may be varied to suit the desires of the manufacturer.

Each member has flaring recesses 8 in its 80 inner side. In the recesses 8 of one member post sections 9 are pivoted and telescope into post sections 10 pivoted in the recesses 8 of the other member 1. These sections exhibit a triangular shape in cross-section as shown in detail in Fig. 4. The 85 ridges of the posts are presented to the leaves A which leaves are provided with triangular marginal notches B somewhat larger than the cross-sectional area of the posts, there being a notch for each post. It 90 is quite obvious that if a leaf is dropped onto the posts, it will position itself if either wall of a notch strikes on the ridge of the correlated post, as indicated by dotted and full lines in Fig. 4.

95 For separating as well as drawing the members 1 and 2 into binding contact with the leaves, swinging extension arms 11 are provided. These arms each include a turn-buckle 12 or its equivalent whereby the 100 length of the arm may be adjusted and the capacity of the binder varied. Each arm is pivoted in a recess 13 of the member 1 and carries at its opposite end an integral worm head 14 centrally pivoted in a recess 17 in the member 2. Each worm head meshes with a worm screw 15 formed on a shaft 16 rotatively confined in the member 2.

The shaft has its ends 18 squared to receive a key 19 whereby it may be rotated. 110

Normally the arms extend between the members at an angle to the posts which latter are at substantially right angles to the members 1 and 2, as shown in Fig. 1. In 5 this position the leaves A are clamped or bound between the members and the ends of said members are flush as are likewise the top and bottom edges of the leaves. Should it be desired to add or remove leaves 10 the key 19 is inserted in one end of the member 2 and engaged over the end 18 of the shaft 16 and the latter rotated by turning the key. The shaft being held against longitudinal displacement within the member 2 begins to traverse the heads 14 by 15 means of the screws 15, which results in the swing of the arms 11. In operating the binder it is placed on its side so that the member 1 forms a support from which the 20 arms swing. As the arms are swung the member 2 is displaced longitudinally whereby the posts are swung laterally to an angle and the arms brought at substantially right angles to the members as shown in Fig. 2. 25 The swinging of the arms from the original angular position moves the member 2 away from the member 1 whereby the leaves are released and the swinging of the posts "fans" the leaves or spreads them into the 30 desired formation shown, in which position may be more readily found by passing the index finger along the top or bottom edges of the leaves.

35 When leaves are inserted or removed it is best to first turn the binder up so that it rests on its back formed by the two members 1 and 2 as shown in Fig. 3. When a leaf is inserted it is readily positioned by 40 means of the triangular notches B and the correspondingly shaped posts. When the removing and inserting of leaves has been completed the binder is again laid on its side with the member 2 uppermost, and by 45 turning the key in the reverse direction the parts are restored to their normal positions

and the leaves bound between the members. It is of course understood that the binder parts are to be covered as is common in the art.

What I claim is:

1. A loose-leaf binder comprising two binder members carrying leaf supports, and means for separating the members and displacing one longitudinally with relation to 55 the other.

2. In a loose-leaf binder, the combination of a plurality of leaves normally having their top and bottom edges flush, and means for binding the leaves together constructed 60 to be actuated to release the leaves and distort their top and bottom edges into a beveled formation.

3. In a loose-leaf binder, the combination of a plurality of loose leaves normally having their top and bottom edges flush, binding members normally clamping the leaves together and capable of movement whereby the leaves are released, and supports carrying the leaves and connected with the members and displaced laterally by the members 70 when the leaves are released, whereby the leaves are fanned.

4. A loose-leaf binder comprising two binder members carrying leaf supports, and 75 means for swinging one of the members with relation to the other to relatively displace one member from the other.

5. A loose-leaf binder comprising two binder members, coöperating leaf posts including elements pivoted to each member, and means for swinging one of the members with relation to the other to relatively displace one member from the other.

6. In a loose-leaf binder, a pair of binder 85 members, telescoping posts pivoted to the members, arms pivoted to and extending between the members, and means for swinging the arms.

In testimony whereof I affix my signature.

JASON B. MOODY.
